UNITED STATES PATENT OFFICE.

GEORGE W. LORD, OF BOSTON, MASSACHUSETTS, ASSIGNOR TO THE LORD
ACOUSTIC TELEPHONE MANUFACTURING COMPANY, OF SAME PLACE.

MECHANICAL TELEPHONE.

SPECIFICATION forming part of Letters Patent No. 359,217, dated March 8, 1887.

Application filed October 20, 1886. Serial No. 216,704. (No model.)

To all whom it may concern:

Be it known that I, GEORGE W. LORD, a citizen of the United States, and a resident of Boston, in the county of Suffolk and State of 5 Massachusetts, have invented a new and useful Improvement in Mechanical Telephones, of which the following is a specification.

This invention is an improvement upon the mechanical telephone described in my application, No. 214,622, for Letters Patent of the 10 United States.

The said invention consists, first, in the combination of a diaphragm with a telephone-case consisting of two sections having said 15 diaphragm between them, said sections being constructed with bell-shaped cavities which flare at their edges to allow the diaphragm to occupy the entire area in cross-section of the case; secondly, in a telephone-case consisting 20 of two sections having the diaphragm between them, and having also elongated cavities in combination with said diaphragm, and a mouth-piece which is inserted in the side of one of said sections above the bottom of its cavity; 25 thirdly, in the combination of a ring, to which the diaphragm is attached, with said diaphragm and said sections, the inner face of the ring being beveled to constitute a continuation of the inner face of one of said sections.

30 In the accompanying drawings, Figure 1 is a view, in longitudinal section, of my improved telephone. Fig. 2 is a view, in elevation, of the same; and Fig. 3 is a detached sectional view showing the call.

35 In these several figures the same letters refer to the same parts.

Referring to the drawings, A is the telephone, which is substantially the same as that described in the application before referred 40 to—that is, it consists of a hollow case, of wood or other suitable material, made in two parts and united together, surrounded by a band of lead or some other suitable non-resonant substance, and divided by a diaphragm, C, of any 45 material suitable for use in a mechanical telephone. The walls of this case form two bell-shaped cavities on each side of the diaphragm, and these cavities are elongated, as shown. The flaring mouths of these cavities allow the 50 diaphragm to be as large as the area of the cross-section of the telephone-case.

B is the conducting-wire, which is attached to the diaphragm by the knob g, as shown. The exterior of this case may have any desired form; but for simplicity and cheapness of construction the cylindrical form shown is preferable. The section b is provided with an opening, D, in its side just above the bottom, which receives the mouth-piece. The lower part, b, of the case may also have attached 55 thereto a flexible tube, E, having an ear or mouth piece attached thereto, which tube may also be used for transmitting and receiving the voice, or both the opening in the side and the flexible tube may be used. This tube and ear-piece are preferably of the form and material used in stethoscopes and instruments for the use of the deaf. The tube is inserted in the bottom of the case below the diaphragm, and terminates within the case in a trumpet-shaped 60 piece, F, of wood, hard rubber, or other suitable material, which extends within the case about half-way to the diaphragm. By the use of this trumpet-shaped attachment I find that the transmission of sound is much facilitated. 65

The diaphragm is stretched over and suitably secured to a wooden ring, d, which is inserted into a recess in the section a, and bears against a shoulder on the same. In order that the diaphragm may extend entirely over the 70 cavity in the section b of the case A, and thus operate with its full effect, the inside of this ring is beveled off.

A suitable calling device is desirable for use with a mechanical telephone. Fig. 3 represents one which I have devised. It consists of a thin plate, f, pivoted in a slot in the side of the section b of the case and projecting from the same, as shown at i. To this plate is attached an arm, e, which terminates in a knob, 90 H, under the end of the conducting-wire. The weight of this arm keeps the knob H from contact with the end of the wire; but by means of the projection i it can be struck against the end of the wire with sufficient force to produce 95 a loud call in the telephone at the other end of the line.

Having thus described my invention, what I claim, and desire to secure by Letters Patent of the United States, is—

1. In combination with the diaphragm of a mechanical telephone, a telephone-case con-

sisting of two sections having said diaphragm between them, said sections being constructed with bell-shaped cavities which flare at their edges from their interior surface to their exterior, to allow the diaphragm to occupy the entire area in cross-section of the case.

2. In combination with a diaphragm, a telephone-case consisting of two sections having the diaphragm between them, and having also 10 cavities elongated in longitudinal section, and a mouth-piece which is inserted in the side of one of said sections above the bottom of its cavity, substantially as set forth.

3. The beveled ring *d* and the diaphragm attached thereto, in combination with the two 15 sections of the telephone-case, the inner face of said ring forming a continuation of the inner face of one of said sections and completing the outward flare thereof.

In witness whereof I have hereunto set my 20 name in the presence of two subscribing witnesses.

GEORGE W. LORD.

Witnesses:

THOMAS F. WELLS,
JOHN H. COOMBS.
